UNITED STATES PATENT OFFICE.

MARION MONROE GREEN, OF COUNTY LINE, TENNESSEE.

CAR-COUPLING.

SPECIFICATION forming part of Letters Patent No. 427,310, dated May 6, 1890.

Application filed January 17, 1890. Serial No. 337,262. (No model.)

To all whom it may concern:

Be it known that I, MARION MONROE GREEN, residing at County Line, in the county of Moore and State of Tennessee, have invented 5 certain new and useful Improvements in Car-Couplings, of which the following is a specification.

My invention has for its object to provide a simple and effective car-coupler which can 10 be easily and quickly operated either from the top or sides of the car, thereby avoiding the necessity of going between the cars to couple.

To this end my invention consists in sundry novel arrangements and peculiar combination of parts, all of which will hereinafter be fully described in the annexed specification and particularly pointed out in the claims, reference being had to the accompanying 20 drawings, in which—

Figure 1 is a perspective view of my improved coupler as applied to one end of a box-car. Fig. 2 is a side view showing the two draw-heads coupled, and Fig. 3 is a detail perspective view of the coupling-pin detached. 25 Fig. 4 is a detail view of a modification.

Referring to the accompanying drawings, A indicates the car, which is provided with a draw-head A' of the ordinary construction. 30 In horizontal brackets a a, extended forward from the end of the car, is held to slide vertically the coupling-bolt B, (shown in detail in Fig. 3,) and which consists of an upper portion B', held in said brackets, and a lower part B², having a jointed connection at b to the lower end of the portion B', said joint being formed by providing the lower end of the part B' with a recess or fork b² to receive a tongue b³ on the upper end of the part B², said end 40 being also formed into an enlargement or head b⁴ to limit the downward movement of said bolt B. By this construction it will be seen that the coupling-pin portion B² will always be moved vertically, even should the part B' be disposed at a slight angle. Between the upper bracket a and an enlargement b⁶ on the part B' is disposed a stout spiral spring C, which normally forces said bolt downward, and to the upper end of said bolt is pivotally 45 connected the outer end d of a foot-lever D, fulcrumed at d' in bearings E E, secured to

the car-top, as shown. About centrally of the part B' is formed a collar or wheel b⁵, with the under face of which is adapted to engage the forwardly-projecting finger f of a rocking lever F, journaled to the end of the cars, said lever being extended to the sides of the car and provided with hand-holds f', as shown.

From the foregoing description, taken in connection with the drawings, it will be seen 60 that when it is desired to couple the cars the brakeman can by depressing the inner end d³ of the foot-lever cause the bolt to be lifted and permit the link to enter the draw-head, and when the draw-heads come together he 65 can quickly remove his foot and permit the spring to force the bolt down in place. It will also be understood that when desired the coupling or uncoupling can be accomplished from the sides of the car by means of the rocking 70 lever shown.

My invention is extremely simple in construction and operation, as in case of an emergency, especially in freight-trains—such as when the engine jumps the track—the brakeman on top of the car, by simply pressing his foot on the lever of any of the cars near the front of the train, can uncouple the major part of the train from the engine in a moment's time. 75

When my improvement is applied to a flat car, I provide the draw-head with a suitably-arranged bracket and dispose the coupling-pin in a manner shown in Fig. 4, the construction and operation of which will be readily 80 understood.

To provide suitable means for automatically coupling the cars, I arrange a roller 10, mounted on a rod 20, secured at its upper end to the connection b³ of the bolt B, said rod extended 90 forward and to the side of the draw-head, as shown. Upon the opposite draw-head I arrange a projecting rod or bar 30, formed with an upturned loop 40, such loop being extended in advance of the coupling-link in such a manner that it will engage the roller 10 as the draw-heads come together and raise the bolt B, and as the link passes into the draw-head the loop will pass beyond the roller 10 and permit the bolt B to be quickly forced down 95 by the spring C, and thereby automatically couple the cars together. 100

Having thus described my invention, what I claim is—

1. The combination, with the car A, provided with horizontal brackets a a , and the draw-head A', of the vertically-movable bolt B, provided with an articulated end B², an enlargement b⁶, a collar or wheel b⁵, the coil-spring C, disposed about said bolt between the enlargement b⁶ and the upper bracket a , the foot-lever D, pivoted upon the top of the car and connected to the bolt, and the rocking lever F, provided with the projection f, adapted to engage the lower face of the collar b⁵, all arranged substantially as and for the purpose described.

2. The combination of the draw-heads A A', each provided with forwardly-projecting members 30, having upturned ends 40, with the vertically-movable spring-actuated bolts B, provided with coupling members at their lower ends, and provided with forwardly-projecting rods 20, adapted to engage the ends 40 of the members 30, whereby the said bolts will be automatically raised in advance of the meeting of the draw-heads, substantially as and for the purpose described.

MARION MONROE GREEN.
